UNITED STATES PATENT OFFICE.

MORRIS DAVIDSON, OF MALDEN, MASSACHUSETTS.

BIDET.

Application filed October 8, 1925. Serial No. 61,291.

This invention relates to bidets and more particularly to a structure of this character which may be very compactly folded and which is very readily assembled when it is 5 desired to use the same.

A further object of the invention is to produce a device of this character having means whereby it may be conveniently filled from the inlet of a bath-tub and may be drained to 10 the outlet of the bath-tub.

These and other objects I attain by the construction shown in the accompanying drawing, wherein for the purpose of illustration is shown a preferred embodiment of 15 my invention and wherein:—

Figure 1 is a perspective view of a bidet constructed in accordance with my invention;

Figure 2 is a longitudinal sectional view 20 therethrough;

Figure 3 is a bottom plan view, the legs being broken away;

Figure 4 is an enlarged sectional view 25 taken through a portion of the side of the seat and the adjacent portion of the tank.

Referring now more particularly to the drawing, the numeral 10 indicates a seat having a central ovato-oblong opening and in accordance with the usual construction of seats 30 of this character reduced in external width intermediate its ends, as at 11, to accommodate the legs of the user. Secured to the under surface of the seat adjacent each end thereof is a pivoted leg structure 12, each 35 including an upper cross bar 13 connecting downwardly diverging legs 14 at the upper ends thereof and a lower cross bar 15 connecting these legs adjacent the lower end thereof. The cross bar 13 of the legs 14, 40 when these legs are perpendicular to the under surface of the seat, will abut against this under surface to limit movement of the legs and prevent further separation of the leg units, it being understood that these leg units, when in their folded position, fold 45 upon the under surface of the seat, the free end of each leg unit moving toward the pivotal connection of the other leg unit to the seat. A longitudinal bar 16 is provided having notches 17 to receive the lower cross bars 15 of the leg units when they are perpendicular to the seat and this cross bar tends 50 to prevent convergence of the legs and accordingly holds this leg and seat structure in 55 a rigid unit.

The numeral 18 designates a tank structure and the bottom of which inclines downwardly toward one end thereof and is at this end provided with a drain opening 19 having communicating therewith a flexible 60 draining tube 20 which may be led to the waste outlet of a bath fitting. The outlet opening 19 may be closed by a removable plug unless the bidet is employed in a bathtub where it is usually employed, in which 65 event, the plug may be dispensed with and the contents of the bidet merely permitted to drain to the waste outlet of the tub. The upper edges of the side walls 12 of the tank are provided with out-turned flanges 22, the 70 end flanges abutting adjacent faces of the upper cross member of the legs to prevent movement of the tank longitudinally of the seat. To the under surface of this seat at one side thereof are rigidly secured slips 23 75 having their inner ends 24 spaced from the lower surface of the seat a sufficient distance to admit the flange 22. At the opposite side of the seat, similar swinging clips 25 are provided pivoted to the seat, as at 26, so that 80 they may be swung over the edge of the flange 22 at the opposite side of the tank to hold the tank in applied position.

To one end of the seat is secured a pivoted 85 clip 27, which serves as a means for securing to the seat the central portion of a length of flexible tubing 28 which is directed longitudinally of the seat and which has the outer end thereof provided with means, as at 29, whereby it may be attached to the faucet of 90 a bath-tub. The free end of this tube may be moved about as desired to direct the stream of water to the desired parts of the body and to fill the tank. It will be noted 95 that this clip is pivoted to the seat, so that it may swing longitudinally thereof and be positioned flatly against the surface of the seat, so that it will not project when the seat is in folded position and that the clip has an opening through which the tube is directed. 100 It will be obvious that when the tube is directed through the clip, any pull upon the tube in either direction will cause the clip to incline about its axis, so that the edges of the opening will come into binding engagement with the tube and prevent accidental slipping thereof. Thus, a means is provided for holding the tube in adjusted 105 positions against accidental displacement.

A structure of this character may be very 110

compactly folded and readily assembled or disassembled. The parts may be kept in a thoroughly sanitary condition without a great amount of labor. The structure is capable of modification in many ways without departing from the spirit of the invention as defined in the appended claim. The tank of the bidet may be made of galvanized iron, copper, nickel-plated, enameled metals, glass, paper, papier-mâché or any other like materials and the frame of the bidet will preferably be made of wood or metal.

I claim:—

In a foldable bidet structure, a seat, supporting legs for the seat hinged to the seat 15 to fold thereagainst, means for securing and bracing the supporting legs in seat supporting position, a tank securable to the under surface of the seat and a clip pivoted to one edge of the seat to swing longitudinally of 20 the seat and having an aperture for the passage of a flexible tube,

In testimony I hereunto affix my signature.

MORRIS DAVIDSON.
